UNITED STATES PATENT OFFICE.

MERRITT GALLY, OF NEW YORK, N. Y.

MECHANICAL MUSICAL INSTRUMENT.

SPECIFICATION forming part of Letters Patent No. 314,012, dated March 17, 1885.

Application filed March 5, 1881. (No model.)

To all whom it may concern:

Be it known that I, MERRITT GALLY, a citizen of the United States, residing in the city of New York, county and State of New York, 5 have invented certain new and useful Improvements in Musical Instruments, of which the following is a specification.

Figure 1 is a section of a portion of an organ, showing passage from the pressure wind-chest to the sounding apparatus, (which may be pipe L,) the valve, exhaust-passage, and a music-sheet, and keys for controlling the exhaust. Fig. 2 shows the diaphragm which controls the valve.

15 In Fig. 1 is shown one of a range of organ-pipes L, the air-passage R C², which supplies the wind from the bellows to all the sounding-valves of the range, one of the sounding-valves D, one of the pneumatic diaphragms A B, and 20 one of the ducts V, which lead from the valves D to the pipes, which ducts are separate from and have no connection with each other. The shutter H is not necessary to the action of the other parts, but is simply a convenient device 25 for shutting off the air from the range of valves D by dividing the air-passage R C² if at any time it should be desirable. The enlarged space R may be termed the "air-trunk" or "air-chest" for conveying the air from the 30 bellows to the sounding-valves, the constricted portion C² being a part of the common air-passage R C².

In the ordinary construction of organs the sounding-valves are placed against the upper 35 surface of the air-passage R C², with the pipe-ducts V placed above the valves, and springs applied to the valves for holding them up against their seats. Instead of this construction, I place a sufficient part of each of the 40 ducts V underneath a part of the air-passage C² to contain the sounding-valves suspended within the ducts V, and to be held up against the valve-seats exterior to the air-passage R C².

I suspend the valve D from a central button, B, forming a part of a flexible diaphragm, A B, in such position that the pressure of air in the passage C² will tend to lift the valve to its seat by pressing upward against the diaphragm. The pressure of the same air downward tends to force valve D from its seat. It

will be seen that if the surfaces of the valve D and diaphragm A B are made of proper comparative dimensions, taking into account the weight of valve and diaphragm, a perfect equilibrium could be produced, so that a slight touch would move the valve up or down.

For operating the valve D, I make a small chamber above the diaphragm A B, which I connect with an exhaust-bellows. I make the surface of the valve D sufficiently larger than that of diaphragm A B to simply overcome their equilibrium, and the valve drops normally from its seat, but may be brought to its seat by a very slight exhaust in the chamber above the diaphragm, through duct e, by means of the exhaust-bellows. I cause valve D to drop again from its seat by venting the chamber above diaphragm A B, and operating the vent either by means of a mechanical music-sheet, as N, or manual key, as I, either 70 or both, as the case may require.

In order that the diaphragm A B may have an extended and easy movement, and be very sensitive for rapid action, I make it of peculiar construction, as shown in Fig. 2, which represents the several parts and the manner of putting them together. In the first part of the figure is shown the diaphragm proper, which is a thin piece of flexible material with a small hole in its center. The material around the 80 edge of the hole is to be stretched to the extent of the dotted lines, thus making the hole larger, and producing a baggy form of the diaphragm. The button B, which is the second part of the figure, is much larger than the 85 original hole in the piece A, and when forced into the hole produces the required stretching. The button B is grooved around its edge to receive the inner edge of the diaphragm. The third and fourth parts of the figure show the 90 flexible piece A and button B connected together, forming the baggy construction, and showing the distance of movement secured by such construction. The baggy shape of the diaphragm allows sufficient movement of the 95 button to produce a full opening of the valve sufficient to sound the larger pipes or reeds of the organ singly or in several sets, as the case may require. If an exhaust-current is desired for producing the tone instead of the pressure- 100

current, I make the valve D slightly smaller than the diaphragm, or make the weight of the valve sufficient to overcome the counterpoise under exhaust, and operate as with pressure, 5 simply using an exhaust instead of a pressure bellows.

What I claim as my invention, and desire to secure by Letters Patent, is—

- 10 1. In a pneumatic action for organs and similar instruments, an air-passage from the wind-chest to the sounding apparatus, a valve in said passage controlling the sounding apparatus, a diaphragm-valve connected with the sound-controlling valve, an exhaust for 15 operating said diaphragm-valve, and mech-

anism, substantially as described, by which the exhaust may be overcome and the sound-controlling valve permitted to open by the pressure, all combined and arranged to operate substantially as described.

2. In an organ-action, the pneumatic consisting of a flexible diaphragm and a button placed therein, the opening in the diaphragm being smaller than the inserted button, whereby a baggy shape of the diaphragm is produced, substantially as described. 20 25

MERRITT GALLY.
